DESIGN FOR A BURIAL CASKET

Chris Larsen, Burlingame, Calif.

Application June 3, 1935, Serial No. 57,104

Term of patent 14 years

To all whom it may concern:

Be it known that I, Chris Larsen, a citizen of the United States, residing in Burlingame, in the county of San Mateo and State of California, have invented a new, original, and ornamental Design for a Burial Casket, of which the following is the specification, reference being had to the accompanying drawing, forming, a part thereof.

Figure 1 is a side view of the burial casket, showing my new design.

Fig. 2 is a top plan view;
Fig. 3 is an end view thereof; and
Fig. 4 is a fragmentary detail view of the handle shown on a larger scale.

I claim:

The ornamental design for a burial casket, as shown.

CHRIS LARSEN.
